UNITED STATES PATENT OFFICE.

AUGUST BENNERSCHEIDT, OF SAN FRANCISCO, CALIFORNIA

FIREPROOF WINDOW-SASH.

No. 865,991.

Specification of Letters Patent.

Patented Sept. 17, 1907.

Application filed January 17, 1907. Serial No. 352,808.

To all whom it may concern:

Be it known that I, AUGUST BENNERSCHEIDT, a citizen of the United States, residing at San Francisco, in the county of San Francisco and State of California, 5 have invented new and useful Improvements in Fire-proof Window-Sash, of which the following is a specification.

This invention relates to improvements in window sashes, the object of the invention being to provide a 10 window sash which will be indestructible by fire, and will therefore tend to prevent the interior of a room catching fire from an adjacent conflagration; which will be neat and attractive in appearance; which will move up and down with little friction; and which will be so 15 constructed as to prevent the access of moisture to the interior of the sash; also to prevent the breakage of the window pane by excessive jar upon the same.

In the accompanying drawing, Figure 1 is a broken front elevation of a window having my improved window sashes therein; Fig. 2 is a vertical section of the same; Fig. 3 is an enlarged horizontal section on the line 3-3 of Fig. 1; Fig. 4 is an enlarged broken front view of a corner of a sash; Fig. 5 is an enlarged horizontal section; Fig. 6 is an enlarged vertical section; 25 Fig. 7 is a broken detail sectional view, showing one of the bolts in side view; Fig. 8 is a sectional view transverse to a spacing strip.

Referring to the drawing, 1 indicates the sides of the window frame, which are preferably made of galvanized 30 sheet steel, hard sheet copper, or the like; and 2 indicates the parting beads, channel shaped in form, and secured to the frame by means of the counter-sunk bolts 3. The lower sash 4 slides between the two parting beads, and the upper sash slides between the rear parting bead 35 and a guide 6 formed by bending the metal of the frame back on itself. The construction of the window frame forms no part of my present invention, which is confined to the sash.

Each window sash has its sides made of channel-shaped sheet metal 7, the inner edges thereof being bent 40 inwards obliquely towards the pane 8. On one or both sides of said pane strips of rubber or other flexible material are interposed between said pane and the edges of the channel shaped sides of the sash whereby moisture 45 is prevented entering the interior of the sash. The said sides are held together by bolts 9, having rounded screw heads 10, and by cap nuts 11, which prevent the access of moisture to the screws, and are conical or tapering in form to avoid engagement with any passing object. 50 Rubber washers 14 are interposed between the nuts 11, and the sides of the sashes. The ends of the sides of the sash are beveled to make a tight joint with each other, said joints being soldered to make them water-tight, and these corners are strengthened by metallic angle- 55 pieces 12, through which the bolts 9 also pass. Around said bolts, between the sides of the channel-shaped sash

frame, are short rubber sleeves 13, the surfaces of which, bearing against the edges of the window pane, prevent any excessive jar upon said edges by said bolts. In each vertical side of each sash near its corners are 60 formed two slots 4, and through said slots small rollers 15 extend slightly beyond the sides of the sash and bear against the sides of the window frame. By reason of this construction, each sash can move very easily in the window frame and I have found that, with such construction, it is not necessary to provide counter-balance weights attached to each side of the sash, but such a weight on one side only is sufficient. The said weight, shown at 16, is attached to a cord or chain 17, which passes around a pulley 18, and is then attached to a loop 70 19 which is secured to one of the bolts 9 which secure the two sides of the sash frame together.

In order to close the space between the two sashes, when the window is closed, there is secured upon each sash frame a spacing strip 20 U-shaped in form, its edges 75 resting against the sash frame, said strip being secured to the sash frame by means of bolts 21 having counter-sunk heads. Said bolts are screwed into nuts 22, into which the bolts 9 from the opposite side of the sash are likewise screwed, as clearly shown in Fig. 8. 80

I claim:

1. In a window sash, the combination, with a window pane, of a frame formed of channel-shaped sheet metal, the edges of which are bent inwards towards said pane, and bolts passing through sides of the channel-shaped frame 85 and drawing said edges against said pane, substantially as described.

2. In a window sash, the combination, with a window pane, of a frame formed of channel-shaped sheet metal, the edges of which are bent inwards towards said pane, bolts 90 passing through sides of the channel-shaped frame and drawing said edges against said pane, and a strip of flexible material interposed between the pane and one of said edges, substantially as described.

3. In a window sash, the combination, with a window pane, of a frame formed of channel-shaped sheet metal, the edges of which are bent inwards towards said pane, bolts passing through sides of the channel-shaped frame and drawing said edges against said pane, and strips of flexible material interposed between said pane and edges, substantially as described. 95

4. In a window sash, the combination, with a window pane, of a frame formed of channel-shaped sheet metal, the edges of which are bent inwards towards said pane, bolts passing through sides of the channel-shaped frame and drawing said edges against said pane, and rubber sleeves 105 around the respective bolts, substantially as described.

5. In a window sash, the combination, with a window pane, of a frame formed of channel-shaped sheet metal, the edges of which are bent inwards towards said pane, bolts passing through sides of the channel-shaped frame and drawing said edges against said pane, and tapering nuts on the ends of said bolts, substantially as described. 110

6. In a window sash, the combination with a window pane of the sash formed of a channel-shaped sheet metal and rollers mounted within said channels at the vertical sides of the sash adjacent to its corners, and extending slightly through said sides to run upon the window frame, substantially as described.

7. In a window sash, in combination with a window frame, a sash frame formed of channel-shaped sheet metal, the edges of which are bent inwards towards the pane, bolts for drawing the sides of said frame together, and a loop attached to one of said bolts and extending out of the frame for attachment to a sash cord, substantially as described.
8. In a window sash, in combination with a window frame, a channel-shaped spacing piece having its edges resting against the sash frame, a nut within the piece, a

bolt through the sides of the frame, and a bolt through said piece, both bolts entering said nut, substantially as described.

In testimony whereof I have hereunto set my hand in the presence of two subscribing witnesses.

AUGUST BENNERSCHEIDT.
